CORROSION RESISTANT ALLOY

Carl Carius, Essen-Rellinghausen, Germany, assignor to Fried. Krupp Aktiengesellschaft, Essen-on-the-Ruhr, Germany

No Drawing. Application September 10, 1936,
Serial No. 100,115. In Germany December 19,
1935

2 Claims. (Cl. 75—125)

My invention relates to corrosion-resistant chromium-nickel-molybdenum-iron alloys having an addition of antimony. These alloys are remarkable for very high resistance to corrosion. 5 For example, their resistance to caustic soda solution or caustic potash solution and especially to hydrochloric acid is far superior to that of the usual chromium-nickel-molybdenum-iron alloys, for example of the known austenitic chromium-nickel-molybdenum steels. The new alloys may 10 be further improved by an addition of copper.

In my co-pending application for Letters Patent, Serial Number 28,943, filed June 28, 1935, 15 which matured into Patent No. 2,054,927 on Sept. 22, 1936, I have already suggested alloys of the following composition:

	Percent
Carbon	0.—1.
Chromium	10.—25.
20 Nickel	20.—40.
Molybdenum	1.—10.
Antimony	2.—7.
Copper	0.—10.
25 Balance iron with or without the normal impurities.	

I have now found that the above-mentioned high resistance to corrosion of these alloys is also obtained already with antimony contents of 30 0.5 to 2%. So, for example, an alloy containing

	Percent
Carbon	0.04
Chromium	13.
Nickel	30.

	Percent
Molybdenum	5.
Copper	5.
Antimony	1.5
Balance iron with the usual impurities	5

has been tested in 25% hydrochloric acid solution at a temperature of 80° centigrade. The loss in weight occurring by this treatment amounted only to from 1 to 2 grammes per sq. meter per hour. 10

Preferably I use alloys of the following composition:

	Percent
Carbon	0.02—0.2
Chromium	10. —20.
Nickel	27. —33.
Molybdenum	2. —5.
Copper	2. —6.
Antimony	0.5 — 2.
Balance iron with or without the normal impurities.	20

What I claim and desire to secure by Letters Patent is:—

1. A chromium-nickel-iron alloy containing 25 0.02—1% carbon, 10.—25% chromium, 20.—40% nickel, 1.—10% molybdenum, 0.5 to less than 2% antimony, 0.1—10% copper, balance iron with or without the normal impurities.

2. A chromium-nickel-iron alloy containing 30 0.02—0.2% carbon, 10.—20% chromium, 27.—33% nickel, 2.—5% molybdenum, 2.—6% copper, 0.5 to less than 2% antimony, balance iron with or without the normal impurities.

CARL CARIUS.
